UNITED STATES PATENT OFFICE

2,267,840

HEEL-BREASTING MACHINE

Fred Ricks and William Arthur Barker, Leicester, England, assignors to United Shoe Machinery Corporation, Borough of Flemington, N. J., a corporation of New Jersey

Application April 24, 1940, Serial No. 331,268
In Great Britain May 19, 1939

34 Claims. (Cl. 12—47)

This invention relates to mechanism for operating upon shoe parts, and is particularly concerned with improvements in machines for breasting heels by means of a reciprocating knife of the type shown, for example, in United States Letters Patent No. 1,117,627, granted November 17, 1914, on an application of Arthur Bates. It is to be understood, however, that the several features of this invention are of general utility and are adaptable for use in any machine for breasting heels by means of a reciprocating knife or for operating upon shoe parts by means of a reciprocating tool.

In the operation of the machine disclosed in the aforementioned patent, the heel to be breasted is held on an open cutting block by hand and is positioned thereon, with respect to the breasting knife, by bringing its top lift into engagement with the knife, which is first lowered to permit this. When the machine is tripped, by means of the continued movement of a hand lever provided for this purpose and also for lowering the knife initially, the knife descends to breast the heel and then returns to its original elevated position, freeing the breasted heel for removal by the operator. Prior to tripping the machine, while the heel is being positioned on the block, and also during the breasting action, the knife is wholly exposed and the danger of injury to the operator is great should the machine be accidentally tripped as the operator is manipulating the knife to locate the heel on the block or should the operator fail to remove his hands from the path of the knife before intentionally tripping the machine to breast the heel.

Accordingly, an object of this invention is to eliminate this danger of operator injury which is inherent in heel-breasting machines of the aforementioned type. Additional objects of this invention are to facilitate the breasting of heels in machines of the kind herein being considered and also to improve the quality of the work done by such machines.

With these objects in view, important features of this invention are the provision, in a heel-breasting machine having a power-operated knife, of an improved loading device for locating, holding and presenting heels to the knife without bringing the hands dangerously close thereto; the provision of a novel safety mechanism, cooperating with the loading device and a movable means for controlling the power drive mechanism to operate the knife; and the provision of an improved knife-guard arrangement cooperating with the novel safety mechanism in

such a manner as to prevent removal of the guard while the knife is operating and to block operation of the knife when the guard is removed.

5 Further features of this invention include; the construction of the loading device in the form of a heel carrier which is readily movable, preferably by swinging about a fixed pivot, from its loading position remote from the breasting knife to a breasting position beneath the knife determined by cooperating locating surfaces on the carrier and a fixed part of the machine; the provision of means for positioning a heel accurately on the carrier in contact with adjustable gages thereon when the carrier is in a loading position remote from the breasting knife and means for clamping the heel securely against displacement while being moved with the carrier to and from breasting position beneath the knife and for holding the heel during the breasting operation; the provision of means cooperating with the carrier and associated with the heel-positioning means for automatically ejecting a breastested heel therefrom; and the provision of means for removing chips and cuttings from the carrier and from the carrier-locating surfaces while the carrier is being returned to loading position.

10 15 20 25 30 35 40 45 50 These and other features of the invention will appear more fully from the following detailed description, when read in connection with the accompanying drawings, and will be pointed out in the appended claims.

In the drawings, Fig. 1 is a front elevation of a heel-breasting machine embodying the present invention, with the loading device in breasting position and the safety mechanism in the position it assumes just prior to the operation of the breasting knife;

Fig. 2 is an elevation of a part of the heel-positioning means of the machine;

Fig. 3 is a side elevation of a portion of the heel-clamping mechanism employed in this machine;

Fig. 4 is a plan view of the loading device shown in Fig. 1, with certain parts indicated in broken lines to illustrate the positions assumed by these parts when the loading device is in its loading position;

Fig. 5 is a plan view of the safety mechanism of the machine with the parts shown in the positions they assume when the loading device is in its loading position and the movable control means blocked;

Fig. 6 is a rear elevation of the parts shown in Fig. 5, with certain elements broken away; and

Fig. 7 is a front elevation of the machine, partly in section and with parts broken away for the sake of clarity.

Before proceeding to a detailed description of the illustrated machine its general construction and mode of operation will be outlined. Referring to Figs. 1 and 7, the machine comprises a frame 1 in which is mounted a slide 3 carrying a breasting knife 4. The slide is reciprocated to operate the knife by a power drive mechanism similar to that disclosed in the aforementioned patent to Bates and which is arranged to be operated by the downward movement of a control rod 109 associated with a safety mechanism indicated generally by the reference character 100. As is usual in power drive mechanisms of this type, the arrangement is such that upon operation by the control rod a single reciprocation of the knife is caused and the parts come to rest with the knife in its original elevated position, as shown in Fig. 1. Before the power drive mechanism can be operated again the control rod must be returned to its original position and the safety mechanism is arranged to do this.

The loading device comprises a carrier 11 arranged to be swung, by an operating handle 23, to a breasting position beneath the knife, as shown in Figs. 1 and 4, and to a loading position remote from the knife, as indicated by the broken-line position of certain of its component parts and a heel H in Fig. 4. The carrier is provided with heel-locating gages 27 and 37 which cooperate with heel-positioning means 45, 45, mounted independently of the carrier and associated with an ejector arm 163, to locate a heel on the carrier when it is in its loading position. A clamping device is also mounted on the carrier, and the operating means for this device is associated with the operating handle of the carrier in such a manner that the operator can clamp the located heel to the carrier and move the carrier to and from loading and breasting positions with one hand.

The safety mechanism is mounted on the right-hand side of the machine and is arranged to block movement of the control rod when the carrier is in any other than breasting position, to release the control rod when the carrier is in breasting position, to lock the carrier in breasting position while the knife is operating, and to prevent the elevation of a knife guard 177 when the carrier is in breasting position and the knife is operating. When the guard is elevated the safety mechanism cannot be operated to release the control rod.

The safety mechanism is also arranged to return the control rod to its original position after a cutting cycle is completed and is itself reset to block operation of the control rod by the return of the carrier to loading position after a breasting operation has been performed. In the illustrated machine, the control rod is spring operated so that when released by the safety mechanism it automatically moves to operate the power drive mechanism, and in this event the machine is continuously operable merely by movement of the carrier to and from loading and breasting positions. However, if desired, the control rod may be moved by means of a foot treadle, or equivalent device, to be tripped by the operator when the carrier has been brought to breasting position and the control rod released.

In the operation of the machine the heel to be

breasted is placed on the carrier when it is in its loading position remote from the breasting knife, as indicated by the broken lines in Fig. 4, and is positioned thereon by the gages on the carrier and the heel-positioning means. The operator then grasps the operating handle of the carrier and the operating means for the clamp mechanism associated therewith with one hand to clamp the heel in place and to swing the carrier to its breasting position. When this position is reached, the safety mechanism releases the rod 109 which is then moved automatically to operate the drive mechanism whereupon the knife is reciprocated to breast the heel. Upon the return of the knife to its upper position, the carrier, which was held against movement by the safety mechanism during the breasting cut, is released, and can be returned to loading position. As the carrier approaches its loading position the heel ejector 163 is operated to eject the heel, the heel-positioning means being simultaneously moved away to permit this operation and subsequently returned to its operative position when this movement is completed. During this return movement of the carrier a pneumatic device 139 is tripped to blow the chips and cuttings from the carrier and from cooperating locating surfaces on the carrier and its supporting means.

Turning to a detailed description of the improved loading device, and referring to Fig. 1, the carrier 11 is mounted on a rotatable stud 17, journaled in an extended portion of a casting 9, for swinging movement about an axis parallel to the direction of movement of the knife 4. This casting is provided with arcuate guiding surfaces 13 mounted for angular movement in the upper portion of a sleeve 7, and is held in adjusted angular position by means of a clamp screw 15. The sleeve 7 is mounted for vertical adjustment on the front of the machine frame 1 and is locked in adjusted position by means of a clamp screw 5. As will be seen from Fig. 4 the carrier is substantially L-shaped and is provided at its left-hand end with the extending operating handle 23 for swinging it between limits determined by an adjustable stop screw 24 and cooperating locating surfaces 77 and 80 provided on the carrier and an extended portion of the sleeve 7, being in operative position when the locating surfaces are together, as indicated in Fig. 4, and in loading position when swung back against the stop screw 24.

The heel gage 27 is shaped to contact the back surface of the top lift of the heel H, and is slidably mounted in a guideway 29 formed in the carrier. An adjusting screw 33, having an operating head 31, is rotatably mounted in the carrier and threaded through a downwardly projecting ear 35 of the heel gage. By turning the screw 33 the position of the gage 27 may be changed to accommodate different sized heels. The gages 37, 37, likewise shaped to engage the top lift, are mounted in a guideway 39 extending across the carrier at right angles to the guideway 29, and an adjusting screw, having a head 38 and provided with right- and left-hand threaded portions 41, 41 is mounted in the carrier and connected to these gages in such manner that by turning the screw 38 the gages may be moved toward or away from each other. The side gages are thus arranged to centralize the heel beneath the knife regardless of its width.

In addition to these heel-locating gages, the machine is provided with heel-positioning means arranged to contact the front surface of the top

lift of the heel, when the carrier is in its loading position, and comprising two fingers 45, 45, which are carried by an arm 47 forming part of a lever 49 secured to a pin 51 pivoted in a forwardly and upwardly extending arm portion of the casting 9. A spring 171 normally holds the lever 49 and its arm 47 in the position shown in Fig. 4 against an adjustable stop 48. The fingers 45, 45 are pivotally mounted in the arm 47 on pins 46, 46 and are geared together as shown. Friction springs 50 bear on the fingers to hold them in adjusted position, see Fig. 2. The arm 47 has a portion 42 slidably mounted on the lever 49, and is adjustable thereupon by means of an adjusting screw 40. A locking screw 44 is arranged to clamp this arm in its adjusted position. These fingers may be brought together or separated to accommodate different sizes of top lifts, and by manipulation of the adjusting screw 40 are positioned to contact the breast surface of the particular size heel being breasted when the carrier is in the loading position and to orient the heel on the carrier with the back and side portions of its top lift in engagement with the gages 27 and 37, 37, which have been suitably adjusted previously. These fingers 45, 45 overlie a cutting block 43, when the carrier is in the loading position shown in Fig. 4 by the broken line outlines of the cutting block, gages 27, 37, and heel H, and assure that the heel will be properly positioned on the carrier.

The wooden cutting block 43 is mounted in a recess on the upper surface of the carrier 11 and underneath it is an adjusting screw 36, accessible through an opening 32, in the end of the carrier, normally closed by a hinged cover 30 held in closed position by a spring latch 34. The imprint of the knife on this block serves as a convenient visual guide for the operator when setting the gages above mentioned, and the heel-positioning means just described. As the cutting block becomes worn during use it may be elevated by means of the adjusting screw 36 and smoothed off flush with the top of the carrier, and, when worn out, may be readily replaced. The adjusting screw extends beneath the lower surface of the carrier, and a clearance slot 236 is provided in the casting 9 to accommodate the adjusting screw when the carrier is moved to breasting position.

Secured to the rotatable stud 17, above the carrier 11, is a bracket 19 in which is pivoted at 57 an arm 55 carrying at its outer end a heel-clamping claw 53. Connected to this arm by a ball end 59 is a rod 61, threaded through a cross-pin 63, see Fig. 3. The cross-pin is journaled in spaced links 65, 65 arranged on opposite sides of the rod 61, and pivotally connected to the carrier by means of pivot-pins 67. Pivoted to these links is a bifurcated rod 71 connected at its outer end to an arm 73 of a lever 75, carried by the operating handle 23, by a nut 70 and a spring 72, interposed between the arm 73 and a washer fixed adjacent to the outer end of the rod. The lever 75 is urged away from the operating handle by means of a spring 74, and a spring 62, see Fig. 1, is positioned between the arm 55 and the upper surface of the carrier 11 to elevate the clamping claw 53 away from the heel when the clamping lever 75 is released. When the clamping lever 75 is moved to the position shown in solid lines in Fig. 4 the rod 71 is pulled to the left, from the position shown in Fig. 3, and the links 65 are swung downwardly about the pivot pins 67 carrying the pin 63 and the rod 61 threaded thereto downward to swing the arm 55

in a clockwise direction, as viewed in Fig. 1, and clamp the claw 53 firmly against the heel H. A stop screw 79, see Fig. 4, limits the opening movement of the lever 75 and the clamp claw 53 may be adjusted by turning rod 61 which is provided with a knurled head 69 for this purpose. As will be observed, the links 65, 65 operate in the nature of a toggle to increase the clamping effect.

10 The ejecting member 163 is mounted on the lever 49 by means of an extension 165 mounted in an enlarged head 161 of the lever. A spring 167 engages a nut 166 carried by the extension 165 in such a manner as to hold a pin 169, associated with the finger 163, in one of a plurality of apertures provided in the head 161. By moving the finger 163 away from the head 161 sufficiently to withdraw the pin, the finger may be indexed to change its vertical position. The pin 51 on which the lever 49 is mounted carries at its lower portion a catch projection 173, and the carrier has on its forward end a spring pawl member 175 for engaging the catch projection, as the carrier is moved from breasting position to loading position, to swing the lever 49 about its pivot 51 and bring the finger 163 to the broken line position shown in Fig. 4 and against the heel to eject it from the carrier into a chute 162. As will be observed, the positioning fingers 45, 45 are at the same time withdrawn from heel-locating position to permit such heel ejection, and the catch projection is arranged to slide by the pawl just before, or when, the carrier reaches its loading position, whereupon the spring 171 returns the parts to the positions shown in Fig. 4.

15 The swingable carrier with its operating handle which is associated with the heel-clamping means enables the operator, with one hand, to clamp the heel to the carrier, to move the carrier to bring the heel under the knife for breasting, and to return the carrier to its loading position where the heel is automatically ejected. Thus, the operator's other hand is free to load heels into the carrier and, since the machine is arranged for automatic operation of the moving 20 control means, the process of heel breasting may be continued without a break and at a speed limited, for practical purposes, only by the ability of the operator to load heels on the carrier, a step rendered simple and easy to perform by the heel-positioning means and clamping means provided. As the heel is securely clamped to the carrier by the clamping means and properly positioned thereon by the heel-positioning means, and since the carrier is always returned to the same position 25 under the knife by virtue of the carrier-locating surfaces and the means for keeping these locating surfaces clear of chips, a high degree of accuracy and quality in the work done is attained.

30 The improved loading device, which has just been described, makes it possible to conveniently and rapidly present heels to the breasting knife, without bringing the hands into dangerous proximity to the knife, and insures uniformly good results because of the accurate positioning, and firm clamping, of the heels on the carrier. The operator is further safeguarded and the breasting operation additionally facilitated by the safety mechanism now to be described.

35 The power drive mechanism for operating the knife is illustrated in Fig. 7 and is similar to the mechanism disclosed in the aforementioned patent to Bates. As this mechanism forms no part of the present invention, it will not be described in detail and reference may be had to the afore-

said patent for such description. In the present arrangement the operating lever 270 (which corresponds to the operating lever 70 of the Bates construction) is extended outwardly through the frame 1 and pivotally connected to the lower end of the control rod 109. A tension spring 110 connected to the frame and to the rod tends to move the rod downwardly to operate the power drive mechanism and cause a single reciprocation of the knife 4. The safety mechanism about to be described controls the movement of rod 109 and thus governs the operation of the knife as will now be explained.

Referring to Fig. 4, a rod 83 having a rounded end is slidably mounted in bracket portions 81 forming extensions of the sleeve member 7, and mounted on one end of the carrier 11 is a projecting flange 84 provided with an inclined and arcuate abutment surface 85. A spring 87, connected to a collar 89 pinned to the rod, and to the lower part of the projecting flange, holds the rounded end of the rod against the abutment surface. Interengaging surfaces on the collar and a part of the frame 1 prevent rotation of the rod. A downwardly extending pin 93, adjustably positioned in a slot 91 in the opposite end of the rod by means of a locking nut 94, projects into a slot 95 formed in the outer end of a lever 97 pivoted at 99 to a bracket member 122 secured to the frame, see Fig. 5. This lever has an extended portion carrying an abutment surface 101 which is positioned beneath an abutment surface 103, carried by a lever 105 pivoted to the bracket 122 on a pivot pin 136, when the carrier is moved from breasting position and the rod 83 shifted to the right from the position shown in Figs. 1 and 4 to the position shown in Figs. 5 and 6. The control rod 109, which upon downward movement operates the power-drive mechanism to cause a single reciprocation of the knife 4, is connected to the outer end of the lever 105 and movement of this rod is blocked when the abutment 101 is beneath abutment 103.

Referring to Figs. 4, 5 and 6, the lever 105 carries a latch pin 111 projecting toward the back of the machine and provided with a latch surface 113. Pivoted to a lever 119, see Fig. 6, journaled on the bracket 122 at 120, is a depending latch 115 having a latch surface 114 for engaging the latch surface 113 of the latch pin 111. A spring 127 tends to hold these latch surfaces in engagement. At its outer end the lever 119 is provided with a bearing surface 121 which rides on a roller 123 journaled on a pin 125 carried by a collar 124 associated with a driving rod 126 for the slide 3. As the slide is reciprocated the lever 119 swings about its pivot 120. Mounted on the lever 97 is a second latch 129 arranged to catch the lower extremity of the first-mentioned latch 115, in the manner shown in Figs. 5 and 6, in which position it is normally held by means of a spring 131. The latch 129 also is provided with a tripping screw 133 adapted to contact a surface 134 on the bracket 122 when the lever 97 is moved to release the lever 105, as will be presently explained.

In Figs. 1 and 4 the parts are shown in the positions assumed when the carrier is in its breasting position, but before the control rod 109 has been moved to operate the power drive mechanism, while in Figs. 5 and 6 the parts are shown in the positions assumed after the carrier is moved from breasting position to loading position and the rod 83 shifted to the right by the abutment surface 85. As shown in the latter figures, the abutting surface 101 of the lever 97

is beneath the surface 103 of the lever 105, and the control rod 109 is thus blocked against downward movement to operate the clutch. Also, the latch 115 now holds the lever 105 against movement to lower the rod 109. As the carrier is moved from loading position toward breasting position the rod 83 is moved to the left by the spring 87 and the lever 97 is swung in a clockwise direction, as viewed in Fig. 5, during which swinging movement the latch 129 removes the latch 115 from beneath the pin 111, thus freeing the lever 105 for downward movement with the control rod when the surface 101 passes beyond the surface 103. By adjusting the pin 93 along the slot 91 in the rod 83, this releasing of the control rod is timed to occur just when the carrier reaches its breasting position as determined by the locating surfaces 77 and 80. The center of curvature of the abutment surface 85 is coincident with that of the guiding surface 13 so that angular adjustment of the carrier will not change this timing relation.

Upon being released the control rod moves downwardly, under the action of spring means 110, Fig. 7, operating the power drive mechanism of the machine to cause a single reciprocation of the knife to breast the heel. As the lever 97 reaches the end of this swinging movement by the carrier 11, the latch 129 is moved, by the engagement of its tripping screw 133 with surface 134, to let go of the latch 115, thus permitting it to swing back against the pin 111. Because of the now lowered position of the pin 111 the latch 115 does not latch, but instead, strikes the pin 113 above its latch surface 113. During the reciprocation of the knife the lever 119 turns about its pivot 120 to lower the latch 115, and upon the return movement of the slide, the pin 111 is engaged by the latch 115 and the lever 105 and rod 109 restored to their original positions at the completion of the breasting cycle. While the knife is operating the lever 105 is in its lowered position, and cooperating surfaces 135 and 137 on the lever 105 and the lever 97 prevent return movement of the lever 97. Since the rod 83 is rigidly connected to this lever and also bears against the abutment surface 85, the carrier is locked in its breasting position during this period. As the carrier is swung to loading position the rod 83 is shifted to the right to reset the lever 97 in blocking position with its abutment surface 101 beneath the surface 103 and with the latch 129 catching hold of the latch 115, as shown in Fig. 5.

Pivoted on trunnions 179 carried by the frame 1 is the knife guard 177, which is arranged to substantially surround the knife 4, and depending therefrom is a rod 181 which is arranged to be moved in a downward direction when the guard is raised against a stop 180 to expose the knife. The lower end 182 of the rod 181 is guided by a projecting bracket 138 formed on the end of the pivot pin 136 so as to move across the path of the lever 97. As will be seen from Figs. 1 and 4, this lever blocks the downward movement of the rod when the carrier is in breasting position and the control rod 109 has been released for operation of the knife. It will also be observed from Figs. 5 and 6 that, when the guard is raised and the rod 181 lowered to the dotted-line position shown in Fig. 6, movement of the lever 97 sufficient to release the control rod 109 is prevented. Thus it is impossible to raise the guard while the knife is operating or to operate the knife while the guard is raised.

Movement of the carrier from breasting position also effects a clearing of chips from the cutting block 43 and from the carrier-locating surfaces by the following mechanism. Mounted on the machine frame at the left-hand side, as viewed in Figs. 1 and 7, is the pneumatic device 139 comprising a cylinder 140, enclosing a spring-operated piston 250, and provided with air ducts 158 and 160. An operating and latching rod 153, pivoted to the piston and urged toward latched position by a spring 252, is connected to the power drive by a hinged rod 157. The lower end of this rod extends through a rounded opening 253 in a projecting arm 241 on a connecting rod 240. As the arm 241 descends, during the breasting operation, it engages an adjustable abutment 158 on the rod 157 and pulls the latching rod down to the position shown whereupon a shoulder 254 on the rod 153 latches on one edge of an opening 255 in the cylinder 140.

Secured to the rod 83, by means of a clamp 143, is a connecting rod 141 pivoted to the end of an arm 145 keyed to a shaft 147. At the opposite end of this shaft is a projection 149 carrying a tripping screw 151. When the carrier is returned from breasting position to loading position the lever 149 is swung by the movement of the rod 83, causing the tripping screw to engage the latching rod and release the spring-operated piston to blow blasts of air through the ducts 158 and 160. These ducts are arranged to direct the air blasts to clean the cutting block 43 and to clear the surface 89 of chips or cuttings, see Fig. 1, thus assuring that the carrier will be returned to the same position under the knife at each operation of the machine and that the block will be kept free of chips.

Having described the invention, what we claim as new and desire to secure by Letters Patent of the United States is:

1. A machine for operating on shoe parts comprising a power-operated reciprocating tool, control means movable to cause operation of said tool, a work carrier movable to a loading position remote from the tool and to an operating position beneath the tool, and means associated with said carrier and said control means operating to block movement of the control means when the carrier is in said loading position and to release the control means for movement to cause operation of the tool when the carrier is in said operating position.

2. A heel-breasting machine comprising a power-operated reciprocating knife, control means movable to cause a single reciprocation of the knife by its power-operating means, a heel carrier movable to a loading position remote from said knife and to a breasting position beneath the knife, and means associated with said carrier and said control means operating to block movement of the control means when the carrier is in loading position and to release the control means for movement to cause reciprocation of the knife when the carrier is in breasting position.

3. A heel-breasting machine comprising a power-operated reciprocating knife, a control means movable to cause a single reciprocation of the knife by its power-operating means, a heel carrier swingable to a loading position remote from said knife and to a breasting position beneath said knife, means for blocking movement of said control means when said carrier is in loading position, and means operable by said carrier for moving said blocking means to release said

control means when the carrier is in breasting position.

4. A heel-breasting machine comprising a power-operated reciprocating knife, a control means movable to cause a single reciprocation of the knife by its power-operated means, a heel carrier movable to a loading position and to a breasting position, means for blocking movement of said control means when said carrier is in loading position, means operable by said carrier for moving said blocking means from blocking position to release said control means for movement to cause operation of said knife when the carrier is in breasting position and for returning said blocking means to blocking position when the carrier is moved to loading position, and means associated with said knife for restoring said control means to its original position, at the termination of the operation of the knife, so that said blocking means can be returned to blocking position.

5. A machine for operating on shoe parts comprising a power-operated reciprocating tool, a control means movable to cause a single reciprocation of the tool by its power-operated means, a work carrier movable to a loading position and to an operating position, means for blocking movement of the control means when the carrier is in loading position, means operable by the carrier for moving the blocking means from blocking position to release said control means for movement to cause operation of the tool when the carrier is in operating position and for returning said blocking means to blocking position when the carrier is moved to loading position, and means associated with said tool for restoring said control means to its original position, at the termination of the operation of said tool, so that said blocking means can be returned to blocking position.

6. A machine for operating on shoe parts comprising a power-operated reciprocating tool, a control means movable to cause operation of said tool, a work carrier movable to a loading position remote from said tool and to an operating position beneath said tool, and means associated with said control means operating to prevent movement of said carrier from operating position when said control means is moved to effect operation of said tool.

7. A heel-breasting machine comprising a power-operated reciprocating knife, a control means movable to cause operation of said knife, a heel carrier movable to a loading position remote from said knife and to a breasting position beneath the knife, and means associated with said control means operating to prevent movement of said carrier from breasting position when said control means is moved to effect operation of said knife.

8. A heel-breasting machine comprising a power-operated reciprocating knife, a control means movable to cause operation of said knife, a heel carrier movable to a loading position and to a breasting position, means for blocking movement of said control means when said carrier is in loading position and for releasing said control means when said carrier is in breasting position, and means associated with said carrier, said control means and said blocking means for preventing movement of said carrier when said control means is moved to cause operation of said knife.

9. A machine for operating on shoe parts comprising a power-operated reciprocating tool, con-

trol means movable to cause a single reciprocation of said tool, a work carrier movable from a loading position to an operating position, a guard substantially surrounding said tool and movable to expose said tool, and means associated with said guard and said control means operating to prevent movement of said guard to expose said tool when said control means is moved and to prevent movement of the control means when said guard is moved to expose the tool.

10. A heel-breasting machine comprising a power-operated reciprocating knife, control means movable to cause a single reciprocation of said knife, a heel carrier movable from a loading position to a breeding position, a guard substantially surrounding said knife and movable to expose said knife, and means associated with said guard and said control means operating to prevent movement of said guard to expose said knife when said control means is moved and to prevent movement of the control means when said guard is moved to expose the knife.

11. A heel-breasting machine comprising a power-operated reciprocating knife, a control means movable to cause a single reciprocation of said knife, a heel carrier movable to a loading position and to a breeding position, a removable guard for said knife, means operable by said carrier to block movement of said control means when the carrier is in loading position and to release said control means when said carrier is in breeding position, and means associated with said guard and cooperating with said blocking means to lock said guard against removal when said blocking means is moved to release said control means and to prevent operation of said blocking means to release said control means when said guard is removed from said knife.

12. A heel-breasting machine comprising a power-operated knife, a control means movable to cause operation of said knife, a heel carrier movable to loading position and to breeding position, a guard substantially enclosing said knife and arranged for movement away from said knife, and safety mechanism associated with said control means and operable by movement of said carrier to block said control means when the carrier is in loading position and to release the control means when the carrier is in breeding position, said safety mechanism including means for locking said guard against movement away from said knife when the knife is operating and for preventing the release of the control means when said guard is moved away from said knife, said safety mechanism also acting to lock said carrier in breeding position while said knife is operating.

13. A machine for operating on shoe parts comprising a power-operated reciprocating tool, a control means movable to cause a single reciprocation of said tool, a work carrier movable between a loading position and an operating position, a pivoted tool guard adapted to be raised to expose said tool, safety mechanism associated with said control means and constructed and arranged to block movement of the control means when said carrier is in loading position and to release the control means when the carrier is in operating position, said safety mechanism also acting to prevent movement of the carrier from operating position while the tool is operating and including means arranged to lock the guard against movement to expose the tool when the tool is operating and to prevent release of the control means when the guard is raised, means

connected to said tool for restoring said control means to its original position after the completion of a single reciprocation of the tool, and means acting upon the return of said carrier to loading position after said tool has been operated to reset said safety mechanism in initial position.

14. A heel-breasting machine comprising a power-operated reciprocating knife, a control means movable to cause a single reciprocation of said knife, a heel carrier movable to loading position and to breeding position, a pivoted knife guard adapted to be raised to expose said knife, safety mechanism associated with said control means and constructed and arranged to block movement of the control means when said carrier is in loading position and to release the control means when the carrier is in breeding position, said safety mechanism also acting to prevent movement of the carrier from breeding position while the knife is operating and including means arranged to lock the guard against movement to expose the knife when the knife is operating and to prevent operation of the knife by the control means when the guard is raised, means connected to said knife for restoring said control means to its original position after the completion of a single reciprocation of the knife, and means operable upon the return of said carrier to loading position after said knife has been operated to reset said safety mechanism in position to block operation of said control means.

15. A heel-breasting machine comprising a power-operated reciprocating knife, a heel carrier movable between a loading position and a breeding position, a control rod for said knife movable to cause a single reciprocation of said knife, safety mechanism associated with said control rod and having a lever normally positioned to block movement of said control rod, and means operated by said carrier when in breeding position to move said lever from blocking position to release said control rod.

16. A heel-breasting machine comprising a power-operated reciprocating knife, a heel carrier movable to a loading position and to a breeding position, a control rod for said knife movable to cause a single reciprocation of said knife, safety mechanism associated with said control rod and with said carrier and including a pivoted lever so connected to said carrier as to control movement of said carrier from its breeding position, and a lever connected to said control rod, said levers being provided with interengaging surfaces constructed and arranged to lock said carrier in breeding position when said control rod is moved to effect the operation of said knife.

17. A heel-breasting machine comprising a power-operated reciprocating breeding knife, a heel carrier movable between a loading position and a breeding position, a control rod movable to cause operation of said knife, safety mechanism associated with said control rod and including a pivoted lever operable by said carrier to block said control rod when the carrier is in loading position and to release said control rod when the carrier is in breeding position, a removable guard for said knife, and means carried by said guard constructed and arranged to strike said lever and prevent removal of said guard when the lever has released said control rod and to prevent movement of the lever by said carrier to release said control rod when said guard is removed to expose said knife.

18. A heel-breasting machine having, in combination, a reciprocating knife, a control rod movable to operate said knife, a heel carrier shiftable between a loading position and a breast position, and safety mechanism for controlling movement of said rod comprising a lever connected to said rod and having a latch pin, a second lever operable by said carrier to block movement of said first lever when said carrier is in loading position and to release said first lever when said carrier is in breast position, said first and second levers having interengaging surfaces for locking said carrier in breast position when said first lever is released, a third lever arranged to be swung upwardly by said knife at the completion of its reciprocation and having a latch engageable with said latch pin, a second latch carried by said second lever constructed and arranged to withdraw said first latch as said second lever is operated to release said first lever and to let go of said first latch when the first lever has been released, and means for returning said first latch to latching position with respect to said latch pin so that said first lever will be returned to its original position by said third lever at the completion of the reciprocation of said knife.

19. A heel-breasting machine comprising a frame, a power-operated reciprocating knife, a control means for said knife, a carrier for loose heels, having heel-clamping and heel-locating means associated therewith mounted on said frame for swinging movement about an axis parallel to the direction of movement of said knife alternately to and from a loading position remote from said knife and a breast position beneath said knife, and manual means for moving the carrier.

20. A heel-breasting machine having, in combination, a frame, a power-operated reciprocating knife, a control means for said knife, a supporting member carried by said frame, and a heel carrier pivoted to said supporting member for swinging movement about an axis parallel to the direction of movement of said knife from a loading position remote from said knife to a breast position beneath said knife, said carrier and said supporting means being provided with cooperating locating surfaces arranged to arrest swinging movement of said carrier when it has reached breast position.

21. A heel-breasting machine having, in combination, a frame, a power-operated reciprocating knife, a control means for said knife, a supporting member carried by said frame, a heel carrier pivoted to said supporting member for swinging movement about an axis parallel to the direction of movement of said knife from a loading position remote from said knife to a breast position beneath said knife, said carrier and said supporting means being provided with cooperating locating surfaces arranged to arrest swinging movement of said carrier when it has reached loading position, and means for removing chips from said cooperating locating surfaces as said carrier is being returned to loading position after said knife has operated.

22. A heel-breasting machine having, in combination, a frame, a power-operated reciprocating knife, a control means movable to cause operation of said knife, a heel carrier pivoted on said frame for movement to and from a loading position remote from said knife and a breast position beneath said knife, and means for lock-

ing said carrier in said breast position during operation of the knife comprising an element engaging said carrier and held against movement by said control means when the control means is moved to cause operation of said knife.

23. A heel-breasting machine having, in combination, a reciprocating breast knife, a heel carrier mounted for swinging movement alternately to and from a loading position remote from said knife and a breast position beneath said knife, manual means for moving the carrier, and means operated by said carrier as it is swung from breast position to loading position for ejecting the heel from said carrier.

15 24. A heel-breasting machine having, in combination, a reciprocating breast knife, a heel carrier mounted for swinging movement alternately to and from a loading position remote from said knife and to a breast position beneath said knife, manual means for moving the carrier, a heel-ejecting device comprising a pivotally mounted arm constructed and arranged when swung about its pivot to strike a heel on said carrier, interengaging means on said carrier and arm operable to swing said arm to eject the heel as said carrier is moved from breast position to loading position, said means operating to release said arm when the carrier reaches loading position, and means for returning said arm to its original position.

25 25. A heel-breasting machine having, in combination, a power-operated reciprocating knife, a heel carrier mounted for movement to a loading position remote from said knife and to a breast position beneath said knife, manual means for moving said carrier, and means associated with said manual means for holding a heel on said carrier during movement thereof and while said heel is being breastfed by the knife.

40 26. A heel-breasting machine having, in combination, a power-operated reciprocating knife, a heel carrier pivotally mounted for swinging movement to a loading position remote from said knife and to a breast position beneath said knife, a handle for moving said carrier, and a heel clamp on said carrier comprising a clamp arm and an operating means therefor, said operating means including a member associated with said handle and having a mechanical advantage connection with said clamping arm, said operating means and said handle being constructed and arranged for operation with one hand to clamp a heel on the carrier and to effect movement of said carrier.

55 27. A heel-breasting machine having, in combination, a frame, a power-operated reciprocating knife, a heel carrier swingable between a loading position remote from said knife and a breast position beneath said knife, heel-locating gages associated with said carrier for locating a heel thereon, and heel-positioning means arranged to contact the breast surface of the top lift of the heel when said carrier is in loading position.

60 28. A heel-breasting machine having, in combination, a frame, a power-operated reciprocating breast knife, a heel carrier swingable between a loading position remote from said knife and a breast position beneath said knife, heel-locating gages on said carrier arranged to contact the back and side portions of the top lift of a heel placed on said carrier, and a plurality of adjustable fingers mounted on said frame for engaging the breast surface of the top lift when

said carrier is in loading position for positioning the top lift against said locating gages.

29. A heel-breasting machine having, in combination, a frame, a power-operated reciprocating breeding knife, a heel carrier swingable between a loading position remote from said knife and a breeding position beneath said knife, heel-locating gages on said carrier arranged to contact the back and side portions of the top lift of a heel placed on said carrier, a plurality of 10 adjustable fingers for engaging the breast surface of the top lift when said carrier is in loading position for positioning the top lift against the locating means, and a heel-ejecting device mounted on said frame, said adjustable fingers being associated with said heel-ejecting device and movable out of the way of the heel when the device is operated to eject a heel from said carrier.

30. A heel-breasting machine having, in combination, a support, a breeding knife, a heel carrier movable on the support to a loading position remote from said knife and to a breeding position beneath said knife, an operating handle on said carrier, adjustable gages on said carrier for engaging the back and side portions of the top lift of a heel, means on the support for engaging the breast surface of the top lift for orienting the heel on the carrier when said carrier is in loading position, and means for clamping the heel on the carrier, said last-named means being associated with the carrier-operating handle in such a manner that the operation of clamping the heel and moving the carrier from loading position to breeding position may be accomplished by one hand.

31. A heel-breasting machine having, in combination, a frame, a breeding knife, a heel carrier mounted on said frame for movement to a loading position remote from said knife and to a breeding position beneath said knife, operating means for said carrier, heel-locating gages on said carrier and a heel-locating device mounted on said frame and arranged to contact the breast surface of the top lift of a heel on the carrier when said carrier is in loading position, heel-ejecting means associated with said heel-locating device and arranged to be operated by said carrier as it is moved to loading position from breeding position, and means for clamping a heel to said carrier, said clamping means being associated with the operating means for said carrier and said heel-locating device being movable out of the way of the heel when said ejecting means is operated.

32. A heel-breasting machine comprising a

power-operated reciprocating knife, a control means movable to cause operation of the knife, a heel carrier movable to a loading position remote from the knife and to a breeding position beneath the knife, said carrier having heel-locating gages and provided with manual means for clamping a heel and for moving the carrier, and a safety mechanism associated with said carrier and said control means and constructed and arranged to block movement of the control means when the carrier is in loading position, to release the control means when the carrier is in breeding position and to lock the carrier in breeding position when the knife is operating.

15 33. A heel-breasting machine comprising a power-operated reciprocating knife, a control means movable to cause operation of the knife, a heel carrier movable to a loading position remote from the knife and to a breeding position beneath the knife, said carrier being provided with heel-locating gages and having manual means operable to clamp a heel and to move the carrier, a heel-ejecting means operable by the carrier and having means for positioning a heel against the gages when the carrier is in loading position, and a safety mechanism associated with said carrier and said control means and constructed and arranged to block movement of the control means when the carrier is in loading position, to release the control means when the carrier is in breeding position and to lock the carrier in breeding position when the knife is operating.

20 34. A heel-breasting machine comprising a power-operated reciprocating knife, a control means movable to cause operation of the knife, a removable guard for said knife, a heel carrier movable to a loading position remote from the knife and to a breeding position beneath the knife, said carrier having heel-locating gages and being provided with manual means for clamping a heel and for moving the carrier, a safety mechanism associated with said carrier, said control means and said guard and constructed and arranged to block movement of the control means when the carrier is in loading position, to release the control means and prevent removal of the guard when said carrier is in breeding position, and to lock the carrier in breeding position when the knife is operating, and means carried by said guard arranged to prevent release of the control means when the guard is removed to expose said knife.
